UNITED STATES PATENT OFFICE.

THOMAS J. DAVIS, OF DUQUESNE, PENNSYLVANIA.

GRATE FOR SINTERING APPARATUS.

Application filed September 23, 1922. Serial No. 590,104.

To all whom it may concern:

Be it known that I, THOMAS J. DAVIS, a citizen of the United States, and resident of Duquesne, in the county of Allegheny and State of Pennsylvania, have invented 5 certain new and useful Improvements in Grates for Sintering Apparatus, of which the following is a specification.

This invention relates to grates, and while 10 not limited thereto, is particularly adapted to grates for use in sintering apparatus, used in sintering blast furnace flue dust, iron ores, and other finely divided materials.

In sintering flue dust, iron ores, etc., the 15 grates of the sintering apparatus become clogged more or less with clinker, cinder, etc. After the apparatus has been tilted to discharge the sintered mass, it has been necessary to spend considerable time and 20 labor to clean out the grates and to remove dust and particles lodged beneath the grates.

One of the principal objects of this invention is to provide a grate, having swinging grate bars adapted to automatically discharge 25 any clinker or other substances clogging the grate, when the pan is tilted, to remove the sintered mass.

Another object is to provide a grate having fixed and swinging bars, said swinging bars being adapted to swing out of alignment with the fixed bars, when the grate is tilted from a horizontal position, and to automatically return to alignment when the grate is returned to a horizontal position.

A further object is to provide a grate in which the swinging bars are removable, thus permitting them to be readily replaced if they become damaged.

These and other objects and advantages 40 will be more clearly brought out in the following specification and claims, and illustrated in the accompanying drawings, in which:

Figure 1 is a top plan of a sintering pan partly broken away, and having some of the grates in position.

Figure 2 is a longitudinal sectional side elevation on the line II—II of Figure 1.

Figure 3 is a sectional elevation on the line III—III of Figure 1.

Figure 4 is a cross section through the sintering pan, showing it in tilted or discharging position, and showing the swinging

grate bars swung out of alignment with the 55 fixed bars.

Figure 5 is a cross section through one of the grate sections.

Figure 6 is a cross section of one of the 60 grate sections on the line VI—VI of Figure 5, showing the swinging grate bars swung or tilted out of alignment with the fixed bars of the section.

Figure 7 is a plan of slightly modified 65 grate members, constructed for use with sintering apparatus of the Dwight-Lloyd type.

Figure 8 is a sectional elevation on the line VIII—VIII of Figure 7.

Figure 9 is a transverse sectional elevation 70 of one of the grates of Figure 7.

In the accompanying drawings, the 75 numeral 2 designates a sintering pan which is arranged to tilt or rock about a horizontal axis, opposite ends of this pan being provided with hollow trunnions 3, 3, by which the pan is rotatably mounted in suitable bearings.

The pan 2 has a bottom 5, sides 6, 6, and 80 integrally formed ends 7, the hollow trunnions 3, 3, opening into the pan through the end walls of the pan. At an intermediate point in the height of the side walls of the pan is a series of grate sections 8, constructed in accordance with this invention. The grate sections 8 are supported vertically 85 by transverse girder supports 9.

The outer ends of the hollow trunnions 3, 3 are connected to one end of suitable 90 conduits 10, which are adapted to have their other ends connected to an exhausting device (not shown) for creating suction, thereby drawing the gaseous products or combustion through the grate sections 8, and along the pan beneath the grate.

The girders 9 have apertures 12 in their 95 web portion to provide for suction or draft along the entire length of the sintering pan.

The grate sections 8 are rectangular in shape, and are arranged in a number of series, longitudinally of the pan. The end 100 grate section of each series is secured to the ends of the pan in any suitable manner and the intermediate sections are each interlocked with each other and with the girder supports 9, as at 14.

Each grate section 8 comprises a rectangular frame portion 15, having a plurality of fixed grate bars 16 formed integrally there-

with and spaced apart a distance greater than their width. Other bars 17 of the same cross sectional areas as the bars 16, are mounted in the spaces between the bars 16 for pivotal movement on a pivot bar 18, which is mounted considerably to one side of the transverse center of the grate sections so that the grate bars 17 are pivoted beyond their horizontal axis. Therefore, when the pan is tilted to discharge the sintered mass, the grate bars 17 will swing outwardly by gravity.

The grate bars 17 are provided with S or ogee curve shaped bearing slots 18^a extending into the bars from the lower face thereof to receive the pivot bar 18. The slots 18^a, due to their novel shape, form a secure mounting of the grate bars 17 on the pivot bar, which permits ready removal when desired, permits free rotation of the grate bars on the pivot bar, and prevents accidental displacement of the grate bars.

The bars 16 and 17 are provided with suitable spacing bosses or shoulders 19 around the bearing slots 18^a to hold the bars in suitable spaced relation.

The bars 16 and 17 are substantially diamond shaped in cross section, being beveled or tapered suddenly from a point above their longitudinal axis toward the center of their top face, and being tapered gradually from the bottom edge of the upper bevel, downwardly toward the center of their bottom face.

The end walls of the frame portion 15 of the grate sections are beveled along their upper edges as at 20, and tapered downwardly from the lower edge of the bevel as at 21. The end of the pivoted grate bars (nearest the pivot bar 18) is cut away as at 22 to allow such end to swing clear of the end of the frame 15, while the other end is formed with a projection 23 overlapping the beveled portion 20 of the adjacent end of the frame 15, and adapted to contact therewith when the grate bars are in horizontal position, thereby supporting the bars 17 in alignment with the bars 16.

Suitable centering lugs 23^a are provided on each side of the pivoted bars 17. These lugs 23^a are adapted to strike the beveled upper faces of the adjacent fixed bars 16 as the pivoted bars swing down into alignment with the fixed bars, thus serving to guide or center the bars as they are seated.

The grate bars 16 and 17 being of the same cross sectional area and held in spaced relation by the spacing bosses 19, it will be apparent that equi-distant spaces are formed between each of the bars 16 and 17 to provide for a draft through the grate sections, while the sintering operation is going on.

The modified grate construction shown in Figures 7 and 8 is particularly designed for continuous sintering machines of the Dwight

and Lloyd type and comprises a rectangular frame member 25 having a plurality of fixed grate bars 26 formed integrally therewith and spaced apart a greater distance than their width. Other grate bars 27 of the same cross sectional area as the bars 26, are mounted in the spaces between the bars 26 for pivotal movement on a pivot bar 28, which is mounted considerably to one side of the transverse center of the grate sections, so that the grate bars 27 are pivoted beyond their horizontal axis. Therefore, when the pan or pallet is tilted to discharge the sintered mass the grate bars 27 will swing outwardly by gravity.

The grate bars 27 are provided with S or ogee curve shaped bearing slots 29 extending into the bars from the lower face thereof to receive the pivot bar 28. The slots 29, due to their novel shape, form a secure mounting of the grate bars 27 on the pivot bar, which permits ready removal when desired, permits free rotation of the grate bars on the pivot bar, and prevents accidental displacement of the grate bars.

The grate bars 26 and 27 are provided with spacing bosses or shoulders 30 around the bearing slots 29 to hold the bars in suitable spaced relation.

Centering lugs 31, provided on each side of the pivoted grate bars 27, are adapted to strike the upper side edges of the fixed grate bars 26 as the pivoted bars swing down into alignment with the fixed bars, thus serving to guide or center the pivoted bars as they are seated.

The front side (that is the side nearest the pivot bar 28) of the frame member 25 is provided with a flange 33 which extends under the grate bars 26 and 27 and is spaced an appreciable distance therefrom. The flange 33 is adapted to form a stop against which the short end of the swinging bars strike when they move outwardly to discharge the sintered mass.

The grates of Figure 7 are shown in position in a pallet of a continuous sintering apparatus which comprises an integrally cast member having sides 35 connected by spaced webs 36 and provided with axle spindles 37 on which are mounted wheels 38 adapted to travel on a suitable track (not shown).

It will be noted that the grate sections are mounted so as to rest directly on the webs 36, and these webs serve to prevent the pivoted bars 27 from moving inwardly or downwardly.

It will, of course, be understood that this invention is not limited to grates for sintering apparatus, nor to a grate composed of sections, since it is adapted to other uses and may be made as an integral grate or in sections, as desired, since each section is in reality a grate complete in itself.

The operation of the grate will be readily understood. As said grate is tilted or turned beyond the vertical, the pivoted grate bars will swing about the pivot bar, due to off center mounting of said grate bars on the pivot. The swinging of the grate bars will dislodge any clinker or other matter lodged in the openings between the bars, and will also provide openings of sufficient width to allow the escape of any matter collected in the pan 2, below the grates.

I claim:—

1. A grate having a plurality of bars, some of said bars being movable and adapted to move out of alinement with the other of said bars when said grate is tilted, said movable bars being removable.
2. A grate having a plurality of parallel bars, some of said bars being rigid and other of said bars being pivoted, said pivoted bars being free to swing out of alinement with said rigid bars when said grate is tilted, said pivoted bars being removable.
3. A grate comprising a frame portion, a plurality of alternating fixed and pivoted bars within said frame portion, a pivot member on which said pivoted bars are mounted, and said pivoted bars being provided with substantially ogee curved bearing slots for the reception of said pivot member.
4. A grate section comprising a frame member having a plurality of fixed bars formed integral therewith, a pivot member mounted in said frame at a point to one side of the transverse center of said grate sec-

tion, and movable bars removably mounted on said pivot member between said fixed bars.

5. A grate section comprising a frame member having a plurality of fixed bars formed integral therewith, a pivot member mounted in said frame at a point to the one side of the transverse center of said grate section, and movable bars provided with ogee curve shaped slots opening from their lower faces to receive said pivot member, said bars being arranged between said fixed bars, and being adapted to swing out of alinement with said fixed bars when said grate section is tilted.

6. A grate section comprising a frame, a plurality of fixed grate bars, a pivot bar, and plurality of pivoted grate bars removably mounted on said pivot bar. 55

7. In a grate section a frame, a pivot bar, and a plurality of pivoted grate bars mounted on said pivot bar, said grate bars being provided with ogee curved bearing slots extending upwardly from their lower face to 60 receive said pivot bar.

8. In a grate section comprising a frame, a plurality of fixed grate bars and a pivot bar, a plurality of pivoted grate bars mounted on said pivot bar, each of said pivoted 65 grate bars being provided with an ogee curved slot for the reception of said pivot bar, and means for limiting the movement of said bars in one direction.

In testimony whereof, I have hereunto set my hand.

THOMAS J. DAVIS.
